CLAIM

The ornamental design for portion of display screen with graphical user interface, as shown and described.

DESCRIPTION

FIG. 1 is a front view of the display screen portion, showing the new design, in a first embodiment;

FIG. 2 is another front view of the display screen portion, with the graphical user interface in a second embodiment;

FIG. 3 is another front view of the display screen portion, with the graphical user interface in a third embodiment;

FIG. 4 is another front view of the display screen portion, with the graphical user interface in a fourth embodiment;

FIG. 5 is another front view of the display screen portion, with the graphical user interface in a fifth embodiment;

FIG. 6 is another front view of the display screen portion, with the user interface in a sixth embodiment;

FIG. 7 is another front view of the display screen portion, with the user interface in a seventh embodiment;

FIG. 8 is another front view of the display screen portion, with the user interface in an eighth embodiment;

FIG. 9 is another front view of the display screen portion, with the user interface in a ninth embodiment; and,

FIG. 10 is yet another front view of the display screen portion, with the user interface in a tenth embodiment.

The broken line in each FIGS. 1-10 represents the outer periphery of the portion of the display screen, and also the outer periphery of the claimed design. The broken line itself forms no part of the claimed design.

1 Claim, 3 Drawing Sheets
